UNITED STATES PATENT OFFICE.

EDWARD A. KLAUSS, OF PITTSBURG, PENNSYLVANIA.

DESIGN FOR A FIRE AND COMBUSTION CHAMBER FOR HOT-AIR FURNACES.

SPECIFICATION forming part of Design No. 32,222, dated February 13, 1900.

Application filed December 19, 1899, Serial No. 740,945. Term of patent 7 years.

To all whom it may concern:

- Be it known that I, EDWARD A. KLAUSS, a citizen of the United States, residing at Pittsburgh, in the county of Allegheny and State of Pennsylvania, have invented a new and original Design for a Fire and Combustion Chamber for Hot-Air Furnaces; and I do declare the following to be a full, clear, and exact description of the invention, such as will enable others skilled in the art to which it appertains to make and use the same, reference being had to the accompanying drawings, and to the figures of reference marked thereon, which form a part of this specification.
- 5 This invention relates to a certain new and original design in a fire and combustion chamber.
- In the views shown like detail parts are designated by numerals of like character.
- o In said views, Figure 1 is a perspective view of my new and original design for a fire and combustion chamber as it would appear when viewed from the front. Fig. 2 is a perspective view of the same as it would appear when viewed from the rear.
- 5 As shown in the drawings, the leading or

material feature of my design consists of a double hollow chamber circular in cross-section and divided into two, the compartments 1 and 2. The lower chamber is of less diameter and greater in length than the upper one and is provided with a square opening 3, located in its wall near its upper end. Where the upper chamber 1 joins the lower chamber 2, a tapering shoulder 4 is formed. The upper end of the chamber 1 is closed by a conical head 5, terminating in a point 6 in the center of the chamber. Upon one side of the upper chamber and near the upper end of the same is the short projecting pipe 7, of small diameter, as shown.

Having described my invention, what I claim as new, and desire to secure by Letters Patent, is—

The design for a fire and combustion chamber, as herein shown and described.

In testimony whereof I affix my signature in presence of two witnesses.

EDWARD A. KLAUSS.
